(57) **CLAIM**

The ornamental design for a video game controller component, as shown and described.

DESCRIPTION

FIG. 1 is an isometric view of a video game controller component showing our new design;

FIG. 2 is a left view thereof;

FIG. 3 is a top view thereof;

FIG. 4 is a back view thereof;

FIG. 5 is a right view thereof;

FIG. 6 is a bottom view thereof;

FIG. 7 is a front view thereof; and,

FIG. 8 is an alternative view thereof.

The broken lines in the drawings depict portions of the video game controller component that form no part of the claimed design.
